UNITED STATES PATENT OFFICE.

WILLIAM WESLEY HICKS, OF SAN FRANCISCO, CALIFORNIA.

DESIGN FOR AN ELECTRIC AIR HEATER.

Application filed May 21, 1928. Serial No. 26,784. Term of patent 14 years.

To all whom it may concern:

Be it known that I, WILLIAM WESLEY HICKS, a citizen of the United States, and a resident of the city and county of San Francisco, State of California, have invented a new, original, and ornamental Design for an Electric Air Heater, of which the following is a specification, reference being had to the accompanying drawing, forming part thereof.

Referring to the drawing:—

The figure is a front perspective of an electric air heater embodying my design.

I claim:

The ornamental design for an electric air heater, as shown.

WILLIAM WESLEY HICKS.
